UNITED STATES PATENT OFFICE.

EMILY TAYLOR, OF NEW YORK, N. Y.

UNION GARMENT.

No. 920,688.

Specification of Letters Patent.

Patented May 4, 1909.

Application filed July 14, 1908. Serial No. 443,503.

To all whom it may concern:

Be it known that I, EMILY TAYLOR, a citizen of the United States of America, and a resident of the borough of Manhattan, city, 5 county, and State of New York, have invented certain new and useful Improvements in Union Garments, of which the following is a specification.

My invention relates to garments worn by 10 females in bathing, gymnasium or other athletic work, and has for its object the production of a princesse garment that will adjust itself to any figure and provide a means of preventing the skirt from flying up.

15 A further object of my invention is to provide a comfortable bloomer made integral with the princesse body that may be readily slipped on and off, with means of suspending the same without the necessity of any belt or 20 belt line, which prevents the bloomers from dragging.

The invention accordingly consists of the features of construction, combination of elements and arrangement of parts, which will 25 be exemplified in the structure hereinafter described, in connection with the accompanying one sheet of drawings forming part of this specification, in which I have represented my princesse one-piece bathing or 30 gymnasium garment embodying the improvements in the preferred form, after which I shall point out more particularly in the claims those features which I believe to be new and of my invention.

35 Referring to the accompanying drawings in which similar characters of reference indicate like parts throughout the several views—Figure 1 is an elevation of my princesse body with the bloomer portion dotted 40 in. Fig. 2 is a front view thereof illustrating a method of opening down the side front seam. Fig. 3 is a back view illustrating the means of suspending the bloomers from their tab which is sewed in the side back 45 seams of the princesse body. Fig. 4 is a section through the crotch of the bloomer illustrating the side body portion of the bloomer leg. Fig. 5 is a front view with the skirt seam opened and the skirt cut away from the 50 bloomer along the lines 20 and 21, showing the bloomer entirely exposed.

In the illustrations I have shown a seven-gore princesse outer garment, but do not wish to limit myself to that particular num-

ber of gores, but a greater or less number of 55 gores may be used as desired to give the required fullness of skirt.

In my bloomers I provide two portions 1 and 2 cut right and left forming legs provided with side body portions 3 and 4 and 60 back tabs 5 and 6 respectively. The side body portions of the bloomers serve not only as a means of suspending the bloomers but also a tight fitted lining to the princesse garment above the imaginary waist line. The 65 leg portions are joined together, in any well-known manner forming a crotch 7 and back seam 8. This back seam extends up and joins the tabs 5 and 6 making a body for the back of the waist of the princesse garment 70 and is sewed into the side back seams of the princesse garment 10 and 11 above the imaginary waist line giving proper support to the bloomers to prevent them from sagging, as will be readily understood by 75 referring to Fig. 5. The side body portions of the bloomers 3 and 4 are joined to the princesse garment at the shoulder seams 12 and 13 and in the under arm seams 14 and 15 respectively, and extend well below the hip 80 to prevent skirt from flying up, as will be readily seen by referring to Fig. 5. In the bottoms of my bloomer legs I provide an elastic band which is common to all bathing suits of this general character and which, 85 therefore, does not require further description. The side body portion 4, and in a similar manner 3, is fastened to the princesse garment above the imaginary line of the 90 waist in side back and side front seams to support the bloomers without the need of a belt, as will be readily seen by referring to Fig. 4. I have illustrated my garment with an opening down the side front seam but any 95 seam of the princesse garment may be used and I do not want to limit myself to that particular position of opening nor to the buttons and button holes for it is obvious that any other well known method of fastening could be employed.

100 The structure above described may be trimmed as desired, the particular features of my invention being the adaptation of the princesse style of garment for bathing having a bloomer made integral without any 105 belt or support of any kind or nature from the hips. The bloomer tab being sewed above the imaginary waist line into the side

back seams of the princesse garment, distributes the weight of the bloomer and prevents them from dragging.

I wish it distinctly understood that my union garment herein illustrated and described is in the form which I desire to construct it, and that any changes or variations may be made as may be convenient or desirable without departing from the salient features of my invention, and I therefore intend the following claims to cover such modification as naturally fall within the lines of invention.

Having thus fully described my invention, what I claim as new and desire to secure by Letters Patent is,—

1. A princesse bathing suit having in combination with the outer garment a two-piece bloomer portion, each piece forming a leg, and side body portion; the leg portions are joined together forming a crotch, and are provided with back tabs which are joined together and to the side back seam of the outer portion, the side body portion of the bloomers is joined to the outer portion in the shoulder seam and in the under arm seam extending down over each hip.

2. A union suit of the class described consisting of a princesse outer garment in com-

bination with a two-piece bloomer portion provided with side bodies and a back extending part way to the collar; the back and side bodies are sewed into the seams of the princesse garment providing a foundation for the latter and suspension for the bloomers.

3. A union suit of the class described, a princesse outer garment, in combination with a two-piece bloomer provided with side bodies, the seams of the side bodies portion made integral with the seams of the outer garment and extending below the hips, whereby the bloomer portion is suspended solely from the shoulders.

4. A union suit of the class described consisting of a princesse garment in combination with a bloomer portion made integral with the outer portion and means of suspending the bloomers through the princesse garment without the use of any belt or belt line.

This specification signed and witnessed in 911 Flat-Iron Building, New York city, this seventh day of July, A. D., 1908.

EMILY TAYLOR.
